SHAFT ROTATING MEANS

Ballard N. Morris, Silver Spring, Md.

Application September 27, 1933, Serial No. 691,202

18 Claims. (Cl. 74—37)

The invention hereinafter disclosed, is an improvement upon and a modification of that set forth in my application Ser. No. 672,487, filed May 23, 1933, which prior application, whether or not it matures into a patent, is hereby made a part hereof and offered for inspection by anyone entitled to inspect the present application, by analogy to "making profert" in judicial proceedings.

Said application, Ser. No. 672,487, discloses the broad idea of rotating a shaft by means of a drum and a band secured to and windable on and off of said drum and also secured to a piston, whose stroke is tangential to said drum; there being means so connecting said drum to said shaft that when the piston forces the band to unwind and turn the drum, this turns the shaft, and when the shaft is further turned it turns the drum in reverse direction, winds up the band and returns the piston and in certain forms disclosed there

20. is a "reversing-drum" and a strap fixed at one end and wound up by the unwinding of the driving-drum band and by the unwinding of the "reversing-drum" strap, the "reversing-drum" reverses the rotation of the driving drum.

25. The present application supplies further means between the piston and the band and between the band and the drum to positively but releasably successively engage the band to the piston, close to the drum, and to the point of tangency, as the band unwinds and to successively, releasably, engage the band to the drum as the band is wound up, and a similar strap engaging means for the "reversing drum", when such drum is employed.

The object of this feature of this invention, is 35 to lessen the length of the tangent or unwound portion of the band or strap that is subject to severe stress, which portion, in the absence of such provision, increases in length as the band or strap is unwound, up to the length of the piston-stroke; 40 also to lessen the compressive strain upon the drum, of the band and to tend to concentrate the pulling stress at the point of tangency.

This application also presents a substitute for the "reversing-drum" and strap, shown in Figs. 45 1, 2, 3, 3½, and 4 to 12 or the toothed reversing pinion, of the other figures of my application Ser. No. 672,487.

As in that application, there are here shown 50 two drums, each of which has a driving band, each of which bands has two pistons which, alternately, pull the band and are pulled back by it, and each drum has a trunnion at each end which trunnions are alined with each other, but eccentric to the drum, so that the trunnions travel 55 in circles as the drums rotate on their own axes.

These trunnions are mounted rotatively and eccentrically in three, alined, rotative disks, at the same distance from the axes of the disks as they are from the axes of the drums. The middle one of these three disks receives the trunnions on the 60 adjacent ends of both drums but at opposite sides of its axis. When either drum is rotated it rotates the intermediate and one end disk by its trunnions and through the intermediate disk, rotates, or revolves, the other drum about the common axis of the disks. One of the end disks is reduced in size and extended through a bearing, as a drive-shaft and the other has simply a journal extension into a bearing, or, may itself be mounted in a bearing. Comparison of the construction so far described with Figs. 3 and 3½ of application Ser. No. 672,487, is invited. But in the present construction, in place of the reversing-drum 348 of said Fig. 3½, there is a crank 70 arm between each drum and each trunnion, extending radially to both and rigidly uniting them and instead of a strap for such drum, there is a fixed surface engageable by the wrist-pin of the crank-arm, so that during the partial rotation of one drum by the other, through the intermediate disk or cylinder, the circular path of travel of the axis of the trunnion toward such fixed surface; the crank wrist-pin being held back by such surface; causes the trunnion, and therefore 75 the drum, to turn in the disk, on the axis of the trunnion, in the opposite direction to the revolution of the trunnion and the drum with the disk.

In the accompanying drawings:

Fig. 1 is a longitudinal, cross-section on a substantially central, vertical plane, of so much of an engine as is necessary to show the relation of my invention thereto. In the right-hand half of this figure the parts are shown in the same relative positions as they are shown in Fig. 5 while in the left-hand half the parts are shown in the same positions as they are shown in Fig. 7 and which is their correct relation to the parts shown at the right.

Fig. 2 shows a transverse vertical section through a piston, a driving-band engaging plate (common to two pistons) the driving band and a driving-drum.

Fig. 3 is a horizontal cross-section of the lower end of a pair of pistons and their common driving-plate.

Figs. 4, 5, 6, and 7 show transverse vertical sections of the parts in four successive positions and are taken in two planes; the plane of the upper part being through the inner end of the right-hand trunnion 15 in Fig. 1, while the plane for

90

95

105

110

the lower part of Figs. 4, 5, and 6, is through the middle of the kidney-shaped support for the drive-drum supporting roller-system, but in Fig. 7 the lower part is sectioned through the connection of the left-hand leg to such support. Fig. 5a shows an end of bar 19, in the position shown in Fig. 5 on a larger scale.

Fig. 8 is a plan view of two rollers of the system of longitudinally sectioned anti-friction rollers; one of the rollers being shown in section.

Fig. 9 is an isometrical, three dimension view of connecting disks for the pintles of the sectional rollers while Fig. 10 is a side view of a pintle in detached relation to its connecting disks, which are shown in section.

Figs. 11 and 12 are sectional views through the reversing-drum part of a trunnion corresponding to the construction of Figs. 1 and 2 of application Ser. No. 672,487 but showing how a cleated band such as shown for the driving-band in Fig. 2 would be applied to a reversing drum.

In Fig. 1 is represented a four-cylinder engine in which the cylinders are grouped in pairs in two water-cooled housings 1, 1, below which project the piston-guiding extensions of the explosion chambers. From these guiding extensions project to the right and the left and then downward, as shown in Figs. 4 to 7, enclosing webs 2, 2, ending in outward turned seating flanges which rest upon and are bolted to like flanges on a hollow base 3. These webs 2, 2, have outwardly bevelled lateral edges 4, 4, (as shown in Fig. 1) upon which seat inwardly bevelled edges of end-capping webs 5, 5, and of an intermediate web 6, all having similar seating flanges bolted to the base flanges and fortifying the cylinder-supporting webs and furnishing a complete enclosure for all the operating parts, but which is removable in sections for inspection or repair purposes. The ends of the end-capping webs form the upper halves of sectional babbeted bearings for the drive-shaft extensions; and the end-capping webs, the intermediate webs and the hollow base have transverse depth-beams or cross-beams 5a, 5a, 6a, 6a, above, and 3a, 3a, 3a, 3a, and 3b, below, which not only strengthen the thinner web parts but also serve other essential purposes described later.

In the left-hand housing 1 there are a pair of pistons designated *a* and *b* and in the right-hand housing 1 a pair of pistons lettered *c* and *d*. Each of these pistons has an extension which (as shown in Figs. 2 and 4 to 7) is flattened on one side to a diametric plane and is also recessed to receive a plate 7 which is as wide as the length of the piston-stroke and seats in the undercut upper end of the recess, so that its front face lies in the said diametric plane of the piston, while its rear face, near its lower end (as shown in Fig. 3) has four rearward projecting ears. From each of three of these ears, 7a, 7b, 7c, project, in the same direction, at right angles to the ears, and parallel to the plate, a cylindrical pin 7e, while through the fourth ear 7d, is a threaded and headed bolt 7f, held by a cross-pin, to swivel in the ear, while its threaded end engages a threaded opening in an adjacent piston wall, so that by turning said bolt in one direction or the other all the cylindrical pins are caused to enter or withdraw from aligned holes in the walls of the two pistons of the pairs *a*, *b*, or *c*, *d*, so that the said plate 7 may rigidly couple said pistons in pairs.

As clearly shown in Fig. 2 the front face of plate 7 has parallel, spaced grooves, the upper

or rear wall, at least, of which has a flat surface, affording a shoulder, which grooves receive cleats or ribs 8, rigid with a band 9, one end of which may be secured to the lower edge of plate 7 by clamp-bar 10 fastened to the plate 7 by screws 11, as shown in Fig. 3. The other end of the band 9 is secured to the periphery of drive drum 12 and as shown in Fig. 2 the surface of this drum is also similarly grooved to receive similar but smaller cleats 8a on the other side of band 9 except that the shouldered side of the grooves on the drum and the shoulder engaging faces of the cleats face in opposite direction from those of the plate. These shoulder engaging cleat-faces are defined by an involute curve so that they engage the shoulders of the plate, as the plate and pistons descend on the power-stroke, just as like faces of gear teeth are engaged by a rack and similarly the shoulders of the grooves on the drum are engaged as the band winds up on the drum. While either set of cleats may be formed integrally with the band, it is preferred that the plate engaging cleats be made separately and welded on and that the weld should extend only a part of the width of the base of the cleat down from its top edge so as to facilitate the curving of the band slightly away from the base of the cleat, as it winds on the drum and so maintain the flexibility of the band. The involute face of the drum-engaging cleats should register with the lower edge of the plate engaging cleats. The angle of the shoulder and the spacing of the cleats relatively to that of the shoulders should be such that the cleats easily enter under the shoulders and intensive pressure is avoided until the shoulder edge intersects that radius of the drum which is normal to the tangent plane of the plate, and the final intensity of pressure need not be reached until the stretch of band between the cleat at this line and the next cleat in advance, has stretched sufficiently to complete the pressure between the cleat and shoulder at the line. In this way, friction between the cleats and shoulders, as they engage and disengage, is lessened and while undue stress on each successive cleat-space of the band can be avoided, a reasonable stress, well within the elastic limits of the steel band, facilitates the engagement and disengagement of the cleats and the shoulders.

Figures 11 and 12 show how a similar arrangement of cleats and shoulders may be applied to a strap, the unwinding of which from a reversing-drum, turns the drive drum oppositely from the driving rotation of the latter, in order to rewind the band on the driving drum. In this case, a horizontal plate 7x is made rigid with a shaft 37 having mounting rollers 37x running on a vertical track 38. This plate is provided with grooves affording shoulders on the right-hand groove wall to engage the involute curved face of teeth or cleats on a strap 36x, one end of which is secured to the shaft 37, while its other end is attached to a reversing-drum 34. An axial extension of this drum constitutes an eccentric trunnion for a driving drum similar to the driving drum 12 of Fig. 2 and having a driving band 9. This trunnion is, similarly eccentrically, mounted in a rotatably journalled disk, corresponding to and axially aligned with the one at the far end of the drum, indicated by 36x. It will be obvious, that with the parts in the positions shown in Fig. 11, the turning of the driving drum by a pull on its band 9 will carry the reversing drum and its trunnion and there-

fore disk 32x clockwise and drum 34x will be moved toward shaft 37 and also (it being rigid with the driving drum) will have the angular motion of a radius of the driving drum, which 5 will wind strap 36x on the reversing drum, until the reversing drum has made a quarter turn. If then, disks 32x continue to be rotated (as by another such driving drum, alined therewith), the reversing drum will move away from the 10 shaft 37 (which is restrained by track 38) and cause a pull on its strap 36x by the shaft 37 and by each shoulder on plate 7x as each successive cleat engages a registering shoulder as the strap unwinds. Such unwinding rotates reversing 15 drum 34 counter-clockwise, about its own axis, in disks 32x and carries driving drum 12 therewith, both rewinding and raising band 9, as shown in Fig. 12. The circular path of travel of the reversing drum 34 includes a vertical as 20 well as a horizontal component and as plate 7x rests on the reversing drum but can travel vertically as facilitated by rollers 37x travelling on track 38, (although said track prevents shaft 36 and plate 7x from moving horizontally) said 25 plate rises and descends with the reversing drum while maintaining the same tangential relation.

A complete structure of duplicate reversing drums for duplicate driving drums is fully set forth in connection with Figs. 1, 2, 3, and 3½ 30 in my application Ser. No. 672,487 and as its general nature has been outlined in the introductory part of this case, and as an equivalent structure, substituting reversing cranks for reversing drums (shown in Fig. 1) is next to be 35 described in detail, it is deemed unnecessary to illustrate a complete structure of reversing drum type.

Returning now to Fig. 1, it will be seen that each drive drum 12 has at each end a radial 40 U-shaped crank-member 13, which (as shown in cross-section at the left-hand end of the left-hand drum) has one end integral with the drum end, and has a large wrist-pin section parallel to the axis of drum 12, and mounts a freely rotatable rim 14, while the other arm of the crank member terminates at its inner end, in a trunnion, parallel to but offset from the axis of drum 12 and between the axes of the drum and the wrist-pin. The trunnions for the outer ends of 45 the drums 12 are designated 15, 15, and each has a short reduced portion terminating in a conical point. Each of these outer trunnions 15, 15, is journalled in a disk 16, at the same distance from the axis of the disk that the trunnion is from the 50 axis of drum 12; the reduced portion of the trunnion projecting through the disk, so that the conical end penetrates a reduced extension of the disk 16, serving to journal the disk in the end 55 bearings provided by the end-capping webs 5, 5, and the base 3. Of these journal extensions of disks 16, one numbered 17, may further project 60 as a drive-shaft, while the other numbered 18, may merely constitute a journal.

At the inner adjacent ends of drums 12, are 65 trunnions 15a, 15a each alined with trunnion 15 of the same drum, but trunnions 15a 15a are longer and have reduced extensions about as long as the unreduced portion, and these trunnions 15a of both drums are journalled in like-shaped bores in a common intermediate disk or 70 cylinder 16a, which bores are equally offset in opposite directions from the axis of said cylinder 16a; the reductions in diameter of the trunnions permitting the larger part of one trunnion to 75 overlap that of the other, while permitting par-

allel engagement of both, co-extensive in length, in cylinder 16a, although the radius of the larger trunnion parts exceeds that of their eccentricity to the cylinder. This disk or cylinder 16a is rotatably mounted in an anti-friction bearing, 80 comprising an inner ring or raceway, which may be keyed or drive-fitted on 16a a sectional roller anti-friction roller system and an outer raceway which seats in a semi-circular recess or half-bearing in the crossbeam 38 of the hollow base 3 85 and may be clamped there by the bolted down cap-piece 3c, as shown in Figs. 4 to 7.

The freely rotatable rim 14 on each wrist-pin of each trunnion carrying crank member 13 is in constant engagement with a movable bar 19; the upper front corner of which is rounded off (and may be cross-ribbed or toothed see Fig. 5a) to rock against the under surface of the cross-beam 5a, 5a, or 6a, 6a, as clearly shown in Figs. 4 and 5. These bars 19 are maintained in constant engagement with the rims 14 by arcuate spiral springs 20 secured to the bars and recedable into arcuate bores in the cross-beams 5a, 5a, 6a, 6a and seating on disks supported by shorter and much more powerful springs 20a, so that as rim 14 moves with crank member 13 from the position shown in Fig. 4, through that shown in Fig. 5 to that in Fig. 6, bar 19 will be rocked up against the gradually increasing resistance of spring 20 until the coils of said spring close into contact with each other, which will be just before the parts reach the position of Fig. 6, when said spring 20 becomes a more or less rigid thrust member which compels the yielding of the heavier spring 20a until the whole upper surface of bar 19 100 105 110 115 120 125 130 135 140 145 150

engages the lower surface of the cross-beam 5a, or 6a, where bar 19 is maintained until after the rim 14 has moved past the position of Fig. 7, to that of Fig. 4.

Attention is called to the fact that as shown in Figs. 2, 3, 4, 5, 6, and 7, the piston extensions are not only flattened in cross-section, diametrically on the side toward the drum 12, but are also flattened on the opposite side or back. This is for the purpose of engaging a large wide roller 21, turning on a shaft 22 suspended by pivoted hangers 23 and bearing against screws 24, by which rollers 21 may be held against the back of the piston, to prevent it from being forced out of line by any pressure against it by drive drum 12, due to the eccentric motion of drum 12, from the position shown in Fig. 7 to that shown in Fig. 4, or to any tendency toward such eccentric motion by said drum during the motion of the drum from its position in Fig. 4 to that of Fig. 5. Obviously screw 24 may be used to pinch the band 9 between drum 12 and plate 7 to supplement the action of the cleats 8 and 8a in lessening the tendency to stretch of band 9, but this would be at the expense of greater frictional resistance to the motion of the piston. Of course rollers 21 might be multiplied along the length of the piston.

While the structure so far described would be fully operative, it is of such great advantage that the supporting of drum 12 be co-extensive with band 9, during the power stroke of a piston, instead of by end bearings laterally of the pistons, that I have shown here, as in my application Ser. No. 672,487, an open bearing, direct support 140 for each drum 12, vertically adjustable, to wholly take the piston thrust off the drive-shaft end-bearings and in Figs 8, 9, and 10. I show modifications of the sectional anti-friction roller arrangement of my earlier application. 145 150

As shown in Figs. 4 and 7, I provide a support 25, kidney-shaped in cross-section, to afford a top surface concentric with drum 12, and as shown in Figs. 1 and 6 mount it on end brackets or legs 5 25a having V-shaped under surfaces resting on and between and dovetailed splined to wedge-blocks 25b, which blocks 25b slide on and are dovetailed splined to the cross-beams 3a of the hollow base 3. Around the support 25 travels 10 an endless series of sectional rollers 26, each roller co-extensive with a drum 12, in length, and the series linked together by a link chain the connecting pivots of which are extensions of pintles on which the roller sections are rotatable. These 15 roller sections of each roller are offset, as in application Ser. No. 672,487, but the means for journaling them in offset relation are somewhat different and are best shown in Figs. 8, 9, and 10. Each section has a pintle 26a; those for the end 20 sections being extended at their outer ends to form the pivots of the connecting links, as shown in Fig. 8, but at the inner ends of these outer pintles and at each end of every intermediate pintle is formed a circumferential shallow concave groove, as shown in Fig. 10, and these 25 grooved ends may be forced into or pulled out of counterpart interiorly convex holes in one of a pair of rigidly united offset connecting disks 26b. These grooved pintle ends may be either 30 fitted so tightly as not to be able to be turned when forced into place, or, so that they may rotate freely in the disk. In the former case before forcing in the pintles, their connecting disks 26b should be so arranged that, except for the middle 35 section, a line connecting the axes of the two disks of a rigid pair at each end of a section of a roller, should occupy such an angle to such a line at the other end of that section that the axes of all the disks would lie in a curve concentric to and intermediate of the curves of the 40 drum 12 and of the upper face of support 25. For the middle roller section the connecting line of the disk pair axes at one end of the section should directly coincide or overlie the line at the 45 other end. In this case as in the construction of my earlier application the sections of each roller would have a permanent curved line relation to each other as shown in Fig. 30 of that application regardless of the position of each roller on the 50 support 25, or elsewhere. But if the pintle fitting permits rotation of the pintle ends in the connecting disks the sections of each roller will automatically assume this curved line relation during their travel between drum 12 and support 25, 55 and elsewhere may assume different relations as exigencies impel. To prevent undue swinging of the roller sections, I show a fixed shell or guard 27 surrounding a part of the kidney-shaped support 25.

The same type of sectional roller series is shown 60 in Figs. 1, and 4 to 7, to be applied to the mounting of the intermediate disk or cylinder 16a, but instead of link chains, (though these could be used) I have shown the outer pintle ends mounted in flat rings.

Description of operation

Assuming that Fig. 4 represents the pair of pistons c, d, to be at the top of their stroke and 70 that a charge is exploded above piston d, the operation would be as follows:

Piston d, descending, forces band driving plate 7 down and this plate being secured to both pistons c and d, as shown in Fig. 3, piston c is also 75 carried down (on a suction stroke). Since to

driving plate 7 is secured the lower end of band 9 by clamp bar 10 and band 9 extends more than halfway around drum 12 and has its other end secured thereto, downward pressure on the drum 12 is initiated and concentrated at the line of tangency of band 9 thereto. The drum 12 is directly supported against bodily downward movement by support 25 (with its system of rollers) in its central vertical plane and for a short distance on each side of that plane, and the tangential pull of band 12 being spaced laterally of the support and the anti-friction rollers facilitating, drum 12 turns and band 9 unwinds. As band 9 unwinds, cleats 8 thereon (see Fig. 2) 80 successively engage shoulders on plate 7, like gear teeth engaging a rack and assume part at least, of the strain upon band 9, while cleats 8a on the inner side of the band, each successively transmits the immediate tangent line pressure of the registering cleat 8 directly to the drum 12, until cleat 8a is disengaged from the drum as the band 9 further unwinds. The axis of trunnion 15 (eccentric to the drum 12) being between the axis of drum 12 and the tangent plane of the band 9, if great resistance to rotation of drum 12 is offered, there may be a tendency of 85 drum 12 to revolve about the axis of trunnion 15 in disk 16, but any such tendency is not only partly resisted by the down pull of so much of band 9 as extends beyond the vertical plane of the axis of drum 12, but also by the fact that the axis being eccentric to the axis of the trunnion, the drum 12 cannot revolve about the axis of the trunnion without forcing plate 7 and both 90 pistons to the right, which is not only resisted by the piston guiding cylinders but by the large rollers 21 at their back. Drum 12 then must rotate on its own axis, when by its rigid trunnions 15, and 15a (which then act only as keys), between the said drum and disk 16 and cylinder 115 16a, respectively, compel both of these to turn on their common axis, which during the entire power-stroke of the piston so turning the drum, is alined with the axis of the drum then under power pressure. When this drum 12 has made 120 a quarter turn, the parts controlled by it, reach the positions of Fig. 5 and there is no longer any tendency for the drum under power to turn on the axis of the trunnion and the whole power imparted to band 9 is directed to rotating the 125 right-hand disk 16 and the cylinder 16a until the parts reach their positions in Fig. 6, the right-hand drum 12 of Fig. 1, so having completed a one-half rotation. Where, as shown in Fig. 1 the drive shaft extension, 17 is at the left, this drive 130 shaft extension is driven by the intermediate cylinder 16a by means of the left-hand drum 12 and its trunnions 15a and 15 and end disk 16; all acting to this end, as a mere prolongation of the drive shaft extension 17, from left-hand disk 16 to the 135 intermediate disk or cylinder 16a. While a gyroscopic action, due to the multiplicity of parts and the eccentric axes of the trunnions and drum, might be feared, all lateral movement of these parts is so controlled, in serving a further purpose, that no such action occurs. While piston d as has just been supposed, moves the parts to the right of the middle in Fig. 1, from the positions shown in Fig. 4, to that of Fig. 5 (which is the position in which they are shown in Fig. 140 1) and then to that of Fig. 6, the parts to the left of the middle in Fig. 1 are moved from the positions shown in Fig. 6, to that of Fig. 7, (and in which they are shown in Fig. 1,) and then to that of Fig. 4, when it is in order for one of the 145 150

left-hand cylinders (as they are shown in Fig. 1,) to be fired causing piston *a* or *b* to descend. Attention is here called to the fact that during the motions of the parts above described, (derived from the supposed descent of piston *d*) from the positions shown in Fig. 4, to that of Fig. 6, cranks 13 have not changed their positions with relation to the cylinder 16*a*, or the end disks 16, but that the slip rims 14, on their wrist-pins have run along the movable bars 19, rocking the latter back and up, gradually compressing springs 20, then as these become more rigid, compressing the much stronger springs 20*a* and finally bringing the bars 19 up into contact with the under surfaces of cross-beams 5*a* and 6*a*, and that this latter positioning of parts which is shown in Fig. 6 is that of the like parts shown at the left in Fig. 1 when the like parts, shown at the right in Fig. 1, are in the position of Fig. 4.

It having been above described that piston *d*, descending, through band 9, turns the right-hand drum (of Fig. 1) a half-rotation, carrying the parts from the position of Fig. 4 to that of Fig. 6 and that intermediate cylinder 16*a* has also revolved trunnion 15*a* of the left-hand drum 12 (of Fig. 1) and necessarily carried said left-hand drum 12, its trunnion 15, and its end disk 16 with it (as a means for rotating drive shaft extension 17) it is now to be noted, what else happens to left-hand drive drum 12 during its revolution with and by the intermediate cylinder 16*a*, which begins with drum 12, crank, 13, and slip-rim 14, in the positions shown in Fig. 6. As both trunnions 15 and 15*a* move from the position shown in Fig. 6 to that shown in Fig. 7 they move about the axis of the intermediate disk or cylinder 16*a*, (because they are eccentric to that) and upward toward the cross-beams 5*a*, 6*a*, but the slip-rims 14 and cranks 13, (whose momentum has been previously gradually reduced by the resistance of springs 20 and 20*a* to the upward movement of bars 19) are held back by bars 19, now resting solidly against the cross-beams 5*a* and 6*a*, and so their angular relation to the end disk 16 and intermediate cylinder 16*a* is shifted counter-clockwise, while the bodily movement of the trunnions continues clockwise with the disk and cylinder. This counter-clockwise shifting of cranks 13, necessarily turns trunnions 15 and 15*a* on their own axes and lifts drum 12 and also turns it until the parts reach the position of Fig. 7 when the drum 12 will have been lifted by the distance of its axis from that of the trunnions, plus the distance of the latter from the axis of the cylinder 16*a* and disk 16 and also turned a quarter-turn counter-clockwise; thereby, through band 9, raising pistons *a* and *b* through the greater part of their return stroke. From this point, trunnions 15 and 15*a* begin to descend but still move to the right, but as drum 12 cannot move bodily to the right because it is in contact, through band 9 with plate 7 the position of which is maintained by both pistons *a* and *b* and by their cylinders and backing rollers 21, 21, drum 12 must be further turned backward or counter-clockwise with reference to the trunnion axes and end disk 16 and cylinder 16*a* and must also descend to the position shown in Fig. 4 which completes the return stroke of pistons *a* and *b*, very slowly because the descending motion so nearly equals in distance the angular final quarter-turn. Both of these motions of the drum 12 are facilitated by the action of springs 20 and 20*a*, which as soon as slip-rims 14 pass the axis of curvature of the

rounding of the upper corner of bar 19 tend to thrust rim 14 and crank-arm 13 counter-clockwise about the axis of the trunnion. I do not regard these springs and bars as necessary to actual operativeness but they are very useful to avoid clatter and shock and absorb momentum and store energy to re-apply it usefully.

It is obvious that, as the left-hand pistons have been described as being returned by the power stroke of a right-hand piston, so the right hand pistons will be returned by a power stroke of a left-hand piston, but in the form shown in Fig. 1 with the drive shaft extension at the left, it will be driven directly by the left-hand drum 12 when that is power-impelled and the only function of the right-hand drum, during this power drive of the left-hand drum is to return the pistons for that drum.

I claim:

1. The combination with a shaft, of a curved-surfaced member, a flexible member attached to the latter, so as to be windable thereon and unwindable therefrom, and means connecting the curved-surfaced member to the shaft, comprising a part moved by the curved surfaced member, but set off from an axis about which the curved-surfaced member moves, so that said part, not only derives an angular motion from said member, but also moves toward and from a fixed point, a fixed element and means relating said part to the fixed element, such that upon turning the curved-surfaced member, as by a pull on the flexible member, when wound thereon, it will turn the shaft to a certain extent and that a further turning of the shaft will turn the curved-surfaced member in the opposite direction and wind up the flexible member thereon; a part of the mechanism above defined being a ribbed or cleated band or strap and a plate having shoulders engaging the ribs or cleats and drawing the band or strap and so successively applying stress to limited stretches of the band or strap.

2. The combination with a shaft, of a curved-surfaced member, a ribbed or cleated band having one end secured to said member so that the band may be wound on by turning the member and the member be then turned by pulling the band, an element movable back and forth and having spaced shoulders to successively engage the said ribs or cleats as the band un-winds and so distribute pressure by said element to successive stretches of the band, and means connecting the curved-surfaced member to the shaft, comprising a part offset from an axis about which said member moves, a fixed element, toward and from which said part is moved by the member as well as given an angular movement, and means relating said part to said element, so that while the shouldered element, by the band, causes the curved-surfaced member to turn a certain amount and so turn the shaft, further turning by the shaft causes the said member to reverse its movement, wind up the band and carry back the shouldered element.

3. A construction such as defined in claim 2 in which the shoulder engaging surfaces of the ribs or cleats, are defined by involute curves and the shoulders co-operate therewith to engage and disengage, as the teeth of a rack co-operate with an involute-toothed gear.

4. A construction such as defined in claim 2 in which the inner surface of the band is also ribbed or cleated and the curved-surfaced member has co-operating shoulders.

5. A construction such as defined in claim 2

in which the inner surface of the band is ribbed or cleated and the curved surfaced member has co-operating shoulders and in which the inner ribs or cleats correspond in spacing with the outer ones.

- 5 6. A construction such as defined in claim 2 in which the inner surface of the band is ribbed or cleated and the curved surfaced member has co-operating shoulders and the spacing of the inner and of the outer ribs of cleats corresponds but the inner are in advance of the outer but by less than the width of the base of an outer rib or cleat.

- 10 7. The combination with a shaft, of a curved-surfaced member eccentrically trunnioned to said shaft parallel to the axis of the shaft and rotatable about either that axis or about one eccentric thereto, a crank arm rigid with said member, a fixed surface intersecting the path of travel of the arm and engageable therewith, a flexible member secured to the curved-surfaced member and windable theron and unwindable therefrom and means so controlling the motion of the curved-surfaced member, that a pull on the flexible member, when wound, will turn the curved-surfaced member and the shaft about the axis of the shaft until the crank-arm engages the fixed surface, when further turning of the shaft will turn the curved-surfaced member backward about the trunnion axis and rewind the flexible member.

- 15 8. A construction such as defined in claim 7 in which the trunnion axis is equally distant from that of the shaft and that of the curved-surfaced member.

- 20 9. A construction such as defined in claim 7 in which means are provided directly engaging the curved-surfaced member and supporting it in the plane of its axis against the pull of the flexible member.

- 25 10. A construction such as defined in claim 7 in which means are provided for directly resisting bodily movement of the curved-surfaced member at a right-angle to the pull of the flexible member.

- 30 11. A construction such as defined in claim 7 in which are provided anti-friction means directly engaging the curved-surfaced member to support it in an axial plane, against the pull of the flexible member and which means travel with the rotation of said curved-surfaced member.

- 35 12. A construction such as defined in claim 7 in which travelling means are provided directly engaging the curved-surfaced member, to support it in the plane of its axis, against the pull of the flexible member and said travelling means are

rollers formed of offset roll-sections pivotally connected, so that the sections of a roller can automatically adapt themselves to the curve of the curved-surfaced member.

- 40 13. A construction such as defined in claim 7 in which means for preventing movement of the axis of the curved-surfaced member transverse to the pull of the flexible member, which means travel with the rotary movement of the curved-surfaced member, are provided.

- 45 14. A construction such as defined in claim 7 in which means are provided between the crank-arm and the fixed surface to absorb the momentum of the crank-arm and apply the energy stored to assist movement of the crank-arm transversely to its arrested motion.

- 50 15. A construction such as defined in claim 7 in which means are provided which maintain an unbroken engagement with the crank-arm, throughout its travel, affording a yielding resistance which stiffens gradually into the positive stop of the fixed surface.

- 55 16. The combination with a pair of circular piston extensions, flattened in cross-section, and recessed to receive and provide an overhanging shoulder for one edge of a plate spanning both piston extensions, and whose exposed surface lies in a plane diametric to the piston circle, means for detachably coupling the plate, adjacent its other edge, to both piston extensions, a band secured to the plate and secured to and winding upon a drum, a shaft assembly comprising said drum and end extensions, and means comprising a part offset from the common axis of the shaft assembly, a fixed element, and means relating to the said part to said fixed element, so that movement of one of said piston extensions and thereby of said plate, partly rotates said shaft assembly, while further rotation of the shaft assembly reversely rotates the drum and returns the plate and piston extensions.

- 60 17. A construction such as defined in claim 16 in which the piston extensions are flattened on two sides and are supported against transverse thrust upon the plate, by a roller, and in which the offset part is a crank-wrist on the drum and the drum has an eccentric pivotal relation to the shaft end-extensions.

- 65 18. A construction such as defined in claim 16 in which the piston pairs are duplicated and the shaft assembly line includes two drums connected to end, and intermediate journaling extensions, by pivots, the pivots of one drum being offset oppositely to those of the other, from the common axis of the extensions.
